UNITED STATES PATENT OFFICE

2,461,162

CAN WASHING MACHINE

Elmer R. Laird, Chicago, Ill., assignor to Armour and Company, Chicago, Ill., a corporation of Illinois

Application December 11, 1944, Serial No. 567,563

10 Claims. (Cl. 134—72)

1

This invention relates to can washing apparatus and more to apparatus for washing, rinsing and drying filled containers such as cans.

In canning food products of many different types the cans or other containers in which the products are packed come from the canning operation or from a cooking operation following canning with their exteriors covered or streaked with various substances. Before the cans are labelled their exteriors must be washed and dried both to permit proper labelling and to improve the appearance of the cans after labelling is completed. Heretofore, this operation has been largely done by hand and was a slow expensive process not always resulting in properly cleaned cans.

One of the objects of the present invention is to provide a can washing apparatus in which the exterior of filled cans is washed, rinsed and dried without requiring any handling of the cans.

Another object is to provide a can washing apparatus which is small and compact and yet which thoroughly cleans and dries the cans.

Still another object is to provide can washing apparatus in which the cans are washed with a re-useable washing liquid and are rinsed with a separate rinsing liquid.

A further object is to provide can washing apparatus in which the cans are dried by the circulation of heated air thereover following washing and rinsing.

A still further object is to provide can washing apparatus in which the cans are automatically picked up and unloaded by the apparatus.

Another object is to provide an apparatus in which the cans are held at an angle so liquid will drain readily therefrom.

The above and other objects and advantages of the invention will be more readily apparent from the following description when read in connection with the accompanying drawings, in which—

Figure 1 is a side elevation of an apparatus embodying the invention with parts broken away;

Figure 2 is a section on the broken line 2—2 of Figure 1;

Figure 3 is a section on the line 3—3 of Figure 1;

Figure 4 is an end elevation of a basket in the loading position on the line 4—4 of Figure 2;

Figure 5 is an end elevation of a basket in the unloading position on the line 5—5 of Figure 2;

Figure 6 is a top plan view of the basket and unloading means of Figure 5; and

Figure 7 is a side view with parts in section

2

showing the manner in which cans are held in the baskets.

The apparatus, as shown, comprises a cabinet indicated generally at 10 which is rectangular in plan and which is vertically elongated. The cabinet is divided by partitions 11, 12 and 13 into a washing compartment 14, a rinsing compartment 15 and drying compartments 16 and 17. The partitions 11 and 13 as seen in Figure 1 terminate below the top of the cabinet while the compartment 12 extends completely to the cabinet top.

The cabinet is preferably supported on a tank 18 which is rectangular in plan and which underlies the entire cabinet. An extension 19 on the tank 18 projects beyond the cabinet and is covered by a hinged door 21 so that the tank may be filled with washing liquid. The top of the tank is open beneath the washing compartment 14 so that washing liquid from the washing compartment may flow freely into the tank. Beneath the rinsing compartment 15, the tank top is closed by a depressed plate 22 forming a sump in which rinsing liquid may collect. The rinsing liquid may be drained from the sump thru a pipe 23 leading to waste. To insure that all of the rinsing liquid is collected in the sump and does not mix with the washing liquid to dilute it, the partitions 11 and 12 may be turned inwardly toward the sump as indicated at 11' and 12' in Figure 1.

Cans to be washed are adapted to be carried thru the cabinet and thru the washing, rinsing and drying compartments in sequence by a conveyor including a pair of horizontally spaced chains 24. The chains pass over spaced sprockets 25 located above the partition 11 under similar spaced sprockets 26 adjacent the lower end of the partition 12 over spaced sprockets 27 at the upper end of the partition 13 and over idler sprockets 28 and 29 in the lower part of the cabinet. Preferably, one set of the sprockets is made adjustable to maintain the chains tight, the sprockets 27 being shown for this purpose as supported by blocks 31 which are vertically adjustable by screws 32 to tighten the chains.

The sprockets and chains are driven by providing a shaft extension on the shaft on which sprockets 26 are mounted and which carries exterior to the cabinet a driving sprocket 33. The driving sprocket 33 meshes with a driving chain 34 driven thru a sprocket 35 by a gear reduction unit 36 and a motor 37. When the motor 37 is running, the chain will be driven to rise in the washing compartment to move downward in the

rinsing compartment, upward in the first drying compartment 16 and downward in the last drying compartment 17.

Cans are carried by the chains thru the several compartments by means of open baskets suspended between the chains on which the cans are adapted to rest. As shown, the baskets are formed of wire or like material with three parallel finger portions 38 of looped wire forming the bottom of the basket connected by a cross bar 39 at one side of the basket. The fingers 38 are bent intermediate their ends so that a can or other container to be washed will rest in the baskets and be carried thereby. To support the baskets on the chains the baskets are formed at their ends with triangular and members connected to the cross bar 39 and formed with eyes 41 pivotally fitting over pins extending inwardly from the chains.

The baskets are so constructed as to carry cans at an angle to the horizontal as best seen in Figure 7. As shown in this figure, the cans indicated at 40 will rest on the finger portions 38 at an angle to the horizontal so that all parts of the can will be subjected to direct action of the washing and rinsing sprays to be described later. Substantially all cans are sealed by means of beads as indicated at 40a and if held with their tops horizontal would tend to accumulate relatively large pools of liquid on their tops so that they could not be dried properly without an unduly extended drying period. By supporting the cans at an angle as shown, the liquid runs off of their tops freely, producing a better washing and rinsing action on the tops of the cans and allowing the cans to be dried quickly and easily.

Cans are adapted to be supplied to the machine by means of a conveyor indicated in section at 42 on Figure 1 and are fed by the conveyor to spaced bars 43 which are adapted to interleave with the fingers 38 of the baskets. In order to prevent the baskets from tilting to drop the can during loading, a guide plate 44 is provided spaced from the ends of the bars 43 and closely adjacent the path of travel of the cross bar 39 on the baskets which will engage the bar 39 to prevent the baskets from tilting to an undesired extent in a counter-clockwise direction. As a can is fed onto the fingers 43, a basket on the conveyor will rise under it and will lift it from the bars and carry it thru the apparatus. Thus the machine may be loaded without manual intervention so that cans which are still hot from the canning or cooking operation can easily be handled without the necessity of an intermediate cooling step.

The completed cans are removed from the apparatus by an unloading means as best shown in Figures 2, 5 and 6. The unloading means comprises a series of triangularly shaped members 45 secured to the partition 13 and extending outwardly with the upper edges of the triangular members 45 sloping downwardly and outwardly from the partition. The members 45 are so spaced as to interleave with the fingers 38 on the baskets so that as a basket travels downwardly the members 45 will engage and lift a can therefrom. After the basket has passed the can may slide from the members 45 to a delivery chute 46 which extends thru a delivery opening in the cabinet. To prevent tilting of the baskets during the delivery operation, side rails 47 are provided which will engage the ends of the basket cross bar 39 if the basket attempts to tilt to limit the permissible tilting thereof. The rails 47 are

spaced as seen in Figure 6 to permit easy passage of a can between them.

As the cans travel upwardly thru the washing compartment 14 they are washed by means of a series of spray nozzles 48 spaced vertically and laterally throughout the washing compartment. The nozzles 48 are supplied from vertical header pipes 49 which are connected at their lower ends to an annular manifold 51. The manifold 51 is supplied thru a pipe 52 by a pump 53 driven by a motor 54. The inlet of the pump is connected thru a pipe 55 to a screen 56 submerged in the tank 18. When the motor 54 is running, washing liquid will be withdrawn from the tank and forced thru the manifold 51, the headers 49 and the several nozzles 48 into the washing compartment. With the nozzles arranged as shown, this compartment will be substantially filled with spray which will strike the cans from all sides as well as from above and below so that the cans will be thoroughly washed. The washing liquid employed may be a mixture of water with any solvent or detergent material according to the substances to be removed from the cans. It will be noted that the major part of the washing liquid employed returns to the tank 18 so that it may be re-used a number of times.

The detergent and any loosened substances remaining on the cans as they travel out of the washing compartment is removed in the rinsing compartment by means of a series of spray nozzles 57 spaced vertically and laterally throughout this compartment. These nozzles may be supplied with any desired rinsing liquid such as water which is fed to the nozzles thru a spray pipe 58. The rinsing liquid together with such materials as are washed from the cans in the rinsing compartment is collected in the trough 22 and is conducted to waste or to other desired points of disposition through the conduit 23.

In order to dry the cans in the drying compartments 16 and 17, air is circulated therethrough. For this purpose a fan 61 is mounted in the upper part of the cabinet adjacent the top of the compartment 17 to force air into the cabinet. A heat exchanger indicated generally at 62 and supplied with heat medium such as steam thru pipes 63, is arranged adjacent the fan 61 to heat the air prior to its entry into the cabinet so that drying of the cans will be accelerated. The air is caused to circulate thru the drying compartment around the cans by means of an exhauster blower 64 whose inlet is connected to the cabinet at the upper part of the rinsing compartment and which discharges thru a conduit 65 outside of the cabinet. With both the fan 61 and the blower 64 running, the heated air forced into the cabinet will pass partially downward thru the compartment 17 and partially across the upper edge of the partition 13 to travel downward thru the compartment 16. The two streams of air will join below the partition 12 and be drawn up thru the rinsing compartment by the blower 64. In this way, it is insured that the air is in contact with the cans a maximum permissible amount of time so that the cans will be thoroughly dried by the time they reach the unloading mechanism.

It will be noted that the arrangement of the several compartments in vertical side-by-side relationship in a single cabinet provides a very compact apparatus requiring a minimum of floor space and yet which will effectively wash, rinse

and dry the cans in a minimum amount of time and without requiring any handling.

While one embodiment of the invention has been shown and described in detail herein, it will be understood that this is illustrative only and is not intended as definition of the scope of the invention, reference being had for this purpose to the appended claims.

What is claimed is:

1. Can washing apparatus comprising a cabinet, vertical partitions therein providing vertically extending washing, rinsing and drying compartments, a conveyor passing vertically through the compartments successively, baskets on the conveyor to carry cans to be washed, means adjacent the entrance to the washing compartment to load cans into the baskets, spray nozzles in the washing compartment to spray washing liquid on the cans as they travel therethrough, spray nozzles in the rinsing compartment to spray rinsing liquid on the cans as they travel therethrough, means to circulate air through the drying compartment to dry the cans as they travel therethrough, and means adjacent to the discharge end of the drying compartment to unload the cans from the baskets.

2. Can washing apparatus comprising a cabinet, vertical partitions therein providing vertically extending washing, rinsing and drying compartments, a conveyor passing vertically through the compartments successively, baskets on the conveyor to carry cans to be washed, means adjacent the entrance to the washing compartment to load cans into the baskets, spray nozzles in the washing compartment to spray washing liquid on the cans as they travel therethrough, spray nozzles in the rinsing compartment to spray rinsing liquid on the cans as they travel therethrough, fan means to blow air into the drying compartment, a heat exchange device adjacent the fan means, and an exhaust blower spaced from said fan means to withdraw air from the cabinet.

3. Can washing apparatus comprising a cabinet, vertical partitions therein providing vertical washing, rinsing and drying compartments, a conveyor passing vertically through the compartments successively, baskets carried by the conveyor formed with spaced parallel fingers to hold the cans to be washed, loading means including spaced parallel bars adapted to interleave with the fingers whereby the baskets can pick up cans from the bars, nozzles in the washing compartment to spray washing liquid on the cans as they travel therethrough, nozzles in the rinsing compartment to spray rinsing liquid on the cans, and means to circulate air through the drying compartment to dry the cans.

4. Can washing apparatus comprising a cabinet, vertical partitions therein providing vertical washing, rinsing and drying compartments, a conveyor passing vertically through the compartments successively, baskets carried by the conveyor formed with spaced parallel fingers to hold the cans to be washed, loading means including spaced parallel bars adapted to interleave with the fingers whereby the baskets can pick up cans from the bars, nozzles in the washing compartment to spray washing liquid on the cans as they travel therethrough, nozzles in the rinsing compartment to spray rinsing liquid on the cans, means to dry the cans as they travel through the drying compartment, and a plurality of spaced sloping fingers adjacent the discharge end of the drying compartment to interleave with

the basket fingers and unload cans from the baskets.

5. Can washing apparatus comprising a cabinet, vertical partitions in the cabinet dividing it into washing, rinsing and drying compartments, horizontally spaced conveyor chains passing vertically through the compartments successively, baskets pivoted at their ends to the chains and lying between the chains to carry cans to be washed through the cabinets, the baskets being formed with spaced parallel fingers to support the cans, loading means adjacent the entrance end of the washing compartment including spaced parallel bars adapted to interleave with the basket fingers, nozzles in the washing compartment to spray washing liquid on the cans as they travel therethrough, nozzles in the rinsing compartment to spray rinsing liquid on the cans as they travel therethrough, and means communicating with the drying compartment for drying the cans as they travel through the drying compartment.

6. Can washing apparatus comprising a cabinet, vertical partitions in the cabinet dividing it into washing, rinsing and drying compartments, horizontally spaced conveyor chains passing vertically through the compartments successively, baskets pivoted at their ends to the chains and lying between the chains to carry cans to be washed through the cabinets, the baskets being formed with spaced parallel fingers to support the cans, loading means adjacent the entrance end of the washing compartment including spaced parallel bars adapted to interleave with the basket fingers, nozzles in the washing compartment to spray washing liquid on the cans as they travel therethrough, nozzles in the rinsing compartment to spray rinsing liquid on the cans as they travel therethrough, means communicating with the drying compartment for drying the cans as they travel through the drying compartment, and unloading means adjacent the discharge end of the drying compartment including spaced parallel bars lying at an angle to the horizontal and adapted to interleave with the basket fingers to remove cans from the baskets.

7. Can washing apparatus comprising a cabinet, vertical partitions in the cabinet dividing it into washing, rinsing and drying compartments, horizontally spaced conveyor chains passing vertically through the compartments successively, baskets pivoted at their ends to the chains and lying between the chains to carry cans to be washed through the cabinets, the baskets having spaced parallel fingers to support the cans, loading means adjacent the entrance end of the washing compartment including spaced parallel bars adapted to interleave with the basket fingers, nozzles in the washing compartment to spray washing liquid on the cans as they travel therethrough, nozzles in the rinsing compartment to spray rinsing liquid on the cans as they travel therethrough, fan means to force air into the drying compartment, a heat exchanger adjacent the fan means to heat the air, an exhaust fan connected to the cabinet at a point spaced from the fan means to cause circulation of the heated air through the drying compartment, and unloading means adjacent the discharge end of the drying compartment to unload dried cans from the baskets.

8. Can washing apparatus comprising walls forming a plurality of vertical compartments, a conveyor passing vertically thru the compartments successively, baskets on the conveyor whose

bottoms consist of spaced angular fingers to hold the cans at an angle to the horizontal, spray nozzles in one of the compartments to spray washing liquid on the cans, spray nozzles in another of the compartments to spray rinsing liquid on the cans, and loading and unloading means at spaced points in the length of the conveyor each including spaced parallel bars to interleave with the fingers in the basket bottom.

9. In a can washing apparatus, a basket adapted to carry a can to be washed comprising a frame having end members connected at one side by a cross bar, means on the end members for pivotal connection to a conveyor, and spaced parallel fingers connected to the cross bar and extending outward therefrom, the fingers bending intermediate their ends to support a can at an angle to the horizontal.

10. In a can washing apparatus, a basket adapted to support a can to be washed comprising connected end members pivotally supported

on a conveyor, and means between the end members forming an openwork basket bottom and bending downward at an angle between the sides of the basket to support a can at an acute angle to the horizontal.
